TEXTILE TRIMMING MATERIAL

Albert K. Billstein, New York, N. Y., assignor to
The First Textile Corporation, New York, N. Y.,
a corporation of New York

Application August 29, 1931. Serial No. 560,064

7 Claims. (Cl. 41—16)

This invention relates to textile trimming material, and an object of the invention is to provide a simple, practical and inexpensive textile trimming material which may be used in place of plumes, also as boas and as ornamental trimmings to garments, hats and the like.

A further object is to have the textile trimming material in the form of a plume or feather and have the appearance of a natural feather and be provided with a quill or seam and barbs or fluff in imitation of a natural feather, while being made of a suitable thread, such as chenille or some other suitable fluffy substance.

15 Another object is to provide the textile trimming material with a central binder to hold its elements together and also, where necessary, to serve as a substitute for and have the appearance of a quill or stem of a feather,

20 Another object is to provide the textile trimming material with lateral binders where a continuous thread is employed in making up the strip of material, the edge binder being designed to keep the strip in shape.

25 Another object is to provide a strip of the textile trimming material with transversely positioned wiry elements, which may be made of horsehair or some wiry glossy material having the form of horsehair, whereby a natural 30 sheen or lustre may be imparted to the strip of material in imitation of the sheen of a feather and whereby said strip may have a degree of transverse rigidity imparted thereto.

Another object is to provide the above described central binder when necessary with a semi-rigid longitudinal re-inforcement, such as a bendable wire or some substance having the properties of a bendable wire to impart to a strip of the textile trimming material the semi-rigidity or partial rigidity of a quill or stem of a feather.

35 A further object is to provide a strip of textile trimming material with superposed transverse layers of barbs to have the appearance of or 40 resemblance to a boa made of either furs or feathers.

Other objects and aims of the invention, more or less specific than those referred to above, will be in part obvious and in part pointed out in 45 the course of the following description of the elements, combinations, arrangements of parts and applications of principles constituting the invention; and the scope of protection contemplated will be indicated in the appended claims.

55 In the accompanying drawing, which is to be

taken as a part of this specification, and in which I have shown merely a preferred form of embodiment of the invention:

Fig. 1 is a fragmentary plan view of one modification of a strip of my textile trimming material.

Fig. 2 is a fragmentary plan view of another modification of a strip of my textile trimming material.

Fig. 3 is a fragmentary plan view of a still other modification of a strip of my textile material.

Fig. 4 is an enlarged section on the line IV—IV of Fig. 1.

Fig. 5 is an enlarged sectional view on the line V—V of Fig. 4.

Fig. 6 is a perspective view of a modification of my textile trimming material having the appearance of a plume; and

Fig. 7 is a fragmentary sectional perspective view of a modification of my textile trimming material having the appearance of a boa.

Referring to the drawing for describing in detail the article which is illustrated therein, the reference character 11 indicates a continuous 50 thread of a suitable fluffy textile substance, such as chenille, and 12 discontinuous lengths of the same thread, employed for forming the main body of my textile trimming material.

A central binding strip 13 is employed in the 55 modifications shown in Figs. 1 and 3 to hold the elements 11 or 12 together in the form of a band or wide strip and to impart thereto a degree of semi-rigidity when desired.

Horse hair looking wiry elements 14, such as 60 horse hair are shown in Figs. 1 and 2 as employed to stiffen the elements 11 and to impart thereto an intermittent lustre or sheen in imitation of the appearance of the barbs of flues of plumage, as in Fig. 3.

The elements 14 may be continuous as in Figs. 1 and 2; they may also be discontinuous, if desired.

In the modification shown in Fig. 2 a pair of lateral binding strips 15 are employed and 100 the central strip 13 of Fig. 1 is omitted.

Lateral binding strips 15 may also be employed in the modification shown in Fig. 1 in addition to the central strip 13.

A central stiffening wire or re-inforcement 16 105 is employed to increase the degree of rigidity of the central strip 13 of Fig. 1 and also to form the core of the central stem 17 of the modification shown in Fig. 6, this stem 17 may be similar in its constituent elements to the 110

strip 13, only being more or less round in shape to have the appearance of a quill or stem of a plume.

In the modification shown in Fig. 3 the threads 12 are discontinuous in order more nearly to resemble barbs of plumes or feathers and are kept together by means of a central binding strip 13.

In the modification shown in Fig. 6 the threads may be in part continuous as at 11 and in part discontinuous as at 12, but preferably discontinuous as at 12.

In the modification shown in Fig. 7 successive layers of strips of textile trimming material such as shown in Fig. 3 may be superposed on each other to form a body similar to a boa. A single pair of binding strips 13 may also be employed to connect transverse layers of threads 12 superposed on each other.

It will be understood that the glossy fibres or horse-hair looking elements 14 are held into the structure by the central binding strip means 13, and by the edge binding strip means 15 when present, that they extend in loose but general parallelism with the threads 11-12 of chenille or the like so that they are more or less promiscuously but evenly distributed throughout the strip and impart a pleasing and attractive sheen to the finished material, as it bends and sways in use, also that they possess a degree of stiffness sufficient so that when attached at both ends as in Figs. 1 and 2 they hold the relatively limp threads of chenille properly distended transversely of the strip and the finished strip normally in a suitably smooth and flat condition.

It will be further understood that wherever a wire is employed the same is intended to be suitably pliable to serve its intended purpose of at once providing a desired stiffness and of holding the strip, and in some instances, the boa, or boa-like material suggested in Fig. 7, in a relatively set position into which it may be bent.

Although the glossy fibres 14 are not directly connected with the threads of chenille they are nevertheless in such close relation thereto that when the finished material is viewed from a little distance they produce in appearance a very satisfactory representation of the small glossy quills of the flies.

In order to further give to the finished material the appearance of a natural feather the wire 16, or the main quill 17, as the case may be, may be made up of a glossy material so that it will more nearly represent the quill of a feather.

As many changes could be made in this construction without departing from the scope of the invention as defined in the following claims, it is intended that all matter contained in the above description, or shown in the accompanying drawing, shall be interpreted as illustrative only and not in a limiting sense.

Having thus described my invention, what I claim as new and desire to secure by Letters Patent is:

1. As an article of manufacture a strip of textile trimming material composed of transversely disposed threads of a fluffy substance aggregated into a strip, and a means for holding the threads together, thereby forming said strip, said holding means comprising central

longitudinal binding means and lateral longitudinal binding means secured to said threads.

2. As an article of manufacture a strip of textile trimming material composed of transversely disposed threads of a fluffy substance aggregated into a strip, and a means for holding the threads together, thereby forming said strip, said holding means comprising central longitudinal binding means and lateral longitudinal binding means secured to said threads, combined with glossy fibres interspersed among the fluffy threads to impart to said strip a degree of lustre the middle portions of said fibres being held in position by said central binding means and the ends of said fibres by said lateral binding means.

3. A strip of textile trimming material, composed of transversely disposed threads of a fluffy substance aggregated into a strip and a central longitudinal binding means for holding said threads together, combined with relatively stiff fibres interspersed among the fluffy threads and connected to said strip, said fibres extending substantially straight from said central binding means transversely to the latter.

4. As an article of manufacture, a strip of textile trimming material composed of transversely disposed threads of a fluffy substance aggregated into a strip, means for holding the threads together in strip formation, and other transversely disposed threads of a non-fluffy glossy material arranged to stiffen said first threads and to impart to the strip a desired lustre.

5. As an article of manufacture, a strip of textile trimming material composed of transversely disposed threads of a fluffy substance aggregated into a strip, means for holding the threads together in strip formation, and other transversely disposed threads of a non-fluffy glossy material interspersed at intervals amongst the first threads and connected therewith so as to stiffen said first threads and to impart to the strip a desired lustre.

6. As an article of manufacture, a strip of textile trimming material composed of transversely disposed threads of a fluffy substance aggregated into a strip, means for holding the threads together in strip formation, and other transversely disposed threads of a non-fluffy glossy material interspersed at intervals amongst the first threads and connected therewith and with said means for holding the threads together thereby to hold the threads in a desired relation to each other and to said means which holds the threads together, and to stiffen said first threads and to impart to the strip a desired lustre.

7. As an article of manufacture, a strip of textile trimming material composed of transversely disposed threads of a fluffy substance aggregated into a strip, means for holding the threads together in strip formation, and a series of relatively stiff fibres interspersed amongst the fluffy threads and connected to said strip, said fibres being connected to the strip at the longitudinal central portion of the strip and each extending laterally of the strip and being connected with the outer end portions of said fluffy threads to serve in holding said threads in position extending transversely of the strip.

ALBERT K. BILLSTEIN.
